UNITED STATES PATENT OFFICE.

OLIVER F. VOSE, OF KALISPELL, MONTANA, ASSIGNOR OF ONE-HALF TO EDWARD J. DICKEY, OF KALISPELL, MONTANA.

DATA-SHEET HOLDER FOR COMPUTING MACHINES AND THE LIKE.

Application filed January 26, 1926. Serial No. 83,890.

My invention relates to computing machines and the like generally, and more particularly to a data sheet holding means for such machines, especially sheets for use in computing taxes, total prices of lumber in quantities, charges for water in cities where water is sold by the gallon, prices of milk and cream at any given rate per gallon, and for such other uses that will suggest themselves from the foregoing.

The general object of my invention is to provide a sheet holding means of the class set forth that will effectively and efficiently support a data sheet in position and easily and readily release the same therefrom as desired or necessary, and which will allow for the employment of sheets of relatively great area, so that a wide range of computations may be obtained from the data displayed thereon.

The manner and means whereby the above and other objects are attained will clearly appear from the specific description of one embodiment of the invention.

Reference is to be had to the accompanying drawings, it being understood that the drawings are merely illustrative of one example of the invention.

Figure 1 is a side elevation of a computing machine embodying my invention;

Figure 2 is a longitudinal vertical section of said machine;

Figure 3 is a cross section in a plane indicated by the line 3—3, Figure 2;

Figure 4 is a perspective view of the inner drum which carries a sheet bearing the table of computations;

Figure 5 is a perspective view of the means for clamping the sheet, bearing the table, in position on the drum;

Figure 6 is a view in the plane indicated by the line 6—6, Figure 4, the view being partly in elevation and partly in section and showing the clamps for holding the sheet on the drum;

Figure 7 is a detail on the line 7—7, Figure 1, showing the detachable engagement of the numbered plates with the keepers at the ends of said plates;

Figure 8 represents a fragment of one example of a chart or sheet contemplated for use with the holder structure.

In carrying out my invention in accordance with the illustrated example, a cylinder 10 is in practice provided with supporting

legs 11. On the front of the cylinder are spaced strips 12 usually of metal, the upper one bearing odd numbers, and the lower one even numbers, which may run upward to any extent available, those shown running respectively to 49 and 50 but the length of the strips and the number of numerals thereon will depend on the size of the machine. Said strips 12 are detachably held at their ends to the cylinder, detachable engagement being effected in the present instance by keepers 13 beneath which the ends of the strips are entered.

On the ends of the cylinder 10 detachable caps 14 are provided turnably fitted on the ends of cylinder 10. Each cap 14 is formed with a preferably non-circular hole 15 to fit over a non-circular or angular formation on the reduced ends 16 of the heads 17 provided on the ends of drum 18 adapted to receive a sheet 19 bearing tables, two lines of said tables appearing at a slot 20 formed in the cylinder 10 between the strips 12 as clearly shown in Figure 1. The screws 21 pass into the reduced ends 16 of heads 17 and overlie the caps 14 to hold said caps tightly on the heads 17, so that with the turning of the caps 14 the heads 17 and the drum 18 will be turned.

A tabulation arranged in longitudinal rows 22 of tables representing amounts of taxes or the like is produced on the sheet 19. The longitudinal edges of said sheet are clamped to the drum 18 by clamp strips 23 disposed longitudinally on said drum. Said clamp strips 23 are integral with springs 24, ends 25 of which are inserted in slots 26. The tendency of the springs 24 is to hold the strips 23 in clamping position. At the opposite ends from the secured ends 25 of springs 24, the latter are inturned radially and lie close to each other as at 27 within slots 27'. Releasing means is provided for the clamp strips 23 and in the illustrated form said releasing means consists of rods 28 having cams 29 disposed beneath the ends of strips 23. On the ends of the rods 28 are operating members in the form of arms 30 which may be depressed to rock the rods 28 to bring the cams 29 in engagement with the clamp strips 23 for lifting said strips.

The numerals on the respective strips 12 represent hundreds or thousands or larger numbers and the table 22 on the sheet 19 comprises the longitudinal lines of computations 110

in associated pairs of lines so that one line of a pair will give the computations of taxes, for example, expressed in hundreds or thousands on one strip 12 and the other line of the 5 pair of computations or tabulations will relate to the numerals on the second strip 12 considering said numerals as expressing hundreds or thousands, for example.

The outer structure 10 has a suitable handle 31 for carrying the machine.

I would state furthermore that while the illustrated examples constitutes a practical embodiment of my invention, I do not limit myself strictly to the exact details herein 15 illustrated, since, manifestly, the same can be considerably varied without departure from the spirit of the invention.

Having thus described my invention, I claim:

- 20 1. In a device of the class described, an elongated cylindrical body adapted to support a data sheet upon the same, clamping means co-extensive with said body beneath which the opposite ends of the sheet are 25 adapted to be secured, attaching members carried by said clamping means and partially encircling said body, said attaching members being engaged with said body to retain said clamping means in their operative positions, 30 and means for actuating said clamping means to release the engaged ends of the sheet.
2. In a device of the class described, an elongated body adapted to support a data sheet upon the same, longitudinal clamping 35 means carried by said body beneath which the opposite ends of the sheet are adapted to be secured, attaching members carried at the opposite ends of said clamping means and partially encircling said body, said attaching 40 members being engaged with said body to retain said clamping means in their operative positions, and means extending within said body for actuating said clamping means to release the engaged ends of the sheet.
- 45 3. In a device of the class described, an elongated cylindrical body adapted to support a data sheet upon the same, clamping means coextensive with said body beneath which the opposite ends of the sheet are 50 adapted to be secured, resilient attaching members secured to the opposite ends of said clamping members and partially encircling said body, said attaching members having portions engaged with said body to retain 55 said clamping means in their operative positions, and means extending within said body for actuating said clamping means to release the engaged ends of the sheet.

- 60 4. In a device of the class described, an elongated cylindrical body, data sheet clamping means extending longitudinally of said body, attaching portions carried by said clamping means and partially encircling the opposite ends of said body and having retaining portions projecting inwardly there-

of, and means extending within said body for actuating said clamping means to release the engaged ends of the sheet.

5. In a device of the class described, an elongated cylindrical body, data sheet clamping means extending lengthwise of said body, attaching portions carried at the opposite ends of said clamping means and partially encircling the opposite ends of said body and having retaining portions projecting inwardly thereof, and means operable outwardly of the peripheral wall of said body for actuating said clamping means to release the engaged ends of the sheet.

6. In a device of the class described, an elongated cylindrical body, data sheet clamping means extending parallel to and at one side of said body, attaching members carried at the opposite ends of said clamping means and partially encircling said body and having retaining portions projecting inwardly thereof, means operable outwardly of said body for actuating said clamping means to release the engaged ends of the sheet, and means for operating said clamp actuating means.

7. In a device of the class described, an elongated cylindrical body, data sheet clamping means laid lengthwise on said body, attaching portions carried at the opposite ends of said clamping means and partially encircling said body and having retaining portions projecting inwardly thereof, means for actuating said clamping means to release the engaged ends of the sheet, and means extending outwardly of the opposite ends of said body for operating said clamp actuating means.

8. In a device of the class described, an elongated cylindrical body, clamping means coextensive with said body and adapted to receive the opposite ends of a data sheet encircled about said body, attaching members supporting said clamping means and partially encircling the opposite ends of said body, cams operable outwardly of the peripheral wall of said body for actuating said clamping means to release the engaged ends of the sheet, and means for operating said cams.

9. In a device of the class described, an elongated cylindrical body, clamping means extending longitudinally of said body to receive the opposite ends of a data sheet encircled about said body, resilient attaching members supporting said clamping means and partially encircling the opposite ends of said body, a member extending lengthwise of said body, cams carried by said member and operable outwardly of the peripheral wall of said body for actuating said clamping means to release the engaged ends of the sheet, and means for operating said member.

10. In a device of the class described, an elongated cylindrical body, clamping means extending longitudinally of said body to re-

ceive the opposite ends of a data sheet encircled about said body, resilient attaching members supporting said clamping means and partially encircling the opposite ends of said body, a rod extending lengthwise of said body and projecting outwardly of the opposite ends thereof, cams carried by said rod and operable outwardly of the peripheral wall of said body for actuating said clamping means to release the engaged ends of the sheet, and operating members carried on the projecting ends of said rod.

11. In a device of the class described, an elongated cylindrical body, parallel clamping members extending longitudinally of and at one side of said body to receive the opposite ends of a data sheet encircled about said body, resilient members carried at the opposite ends of each of said clamping members and partially encircling the opposite ends of said body, cams operable outwardly

of the peripheral wall of said body for actuating said clamping means to release the engaged ends of the sheet, and means for operating said cams.

25

12. In a device of the class described, a rotatable elongated body, parallel clamping members supported longitudinally on said body at one side thereof to receive the opposite ends of a data sheet encircled about said body, resilient attaching members carried at the opposite ends of each of said clamping members and partially encircling said body in opposite directions thereon, means carried at the opposite ends of each of said attaching means and engaged with said body, members operable outwardly of said body for actuating said clamping members to release the engaged ends of said data sheet, and means extending through said body for actuating said last-mentioned members.
